UNITED STATES PATENT OFFICE.

WILLIAM E. HUBBARD, OF SAN FRANCISCO, CALIFORNIA, ASSIGNOR TO HUBBARD MACHINE COMPANY, A COPARTNERSHIP CONSISTING OF WILLIAM E. HUBBARD AND LEON SLOSS, JR., OF SAN FRANCISCO, CALIFORNIA.

PUMPING SYSTEM.

Application filed May 4, 1925. Serial No. 27,728.

This invention relates to pumping systems and particularly to an improved fluid operated pumping system. In pumping systems of the reciprocating type for use on oil or other deep wells, considerable power is necessary, and such power is exerted intermittently, being used only on the up stroke of the pump. The weight of the pump and sucker rods is usually considerable, and this weight operates the mechanism by gravity on the downward stroke. The primary object of my invention is to provide a fluid operated pumping system wherein a continuously operating pump functions to continuously store up energy in the form of a fluid under pressure, which fluid reacts to intermittently raise the said pump rods on the upward stroke. Obviously such a system requires a smaller pumping unit, since the same operates continuously and the operation of such a system is smoother and more uniform than the intermittently operating system heretofore used, and has other material advantages, as will hereinafter appear.

In my Patent Number 1,465,671, dated August 21, 1923, I have disclosed a pumping system wherein the weight of the sucker rods and the co-operating mechanism are counterbalanced, whereby the surplus energy of the downward stroke thereof is stored up in the form of a compressed fluid and which fluid reacts on the rods on the upward stroke to assist in raising the same. It is a further object of my invention to combine this patented system with the improved pumping system of my present invention. These two systems combined comprise a pumping system in which the pump and pump rods are counterbalanced and operated by fluid pressure and to which power for the operation thereof is furnished by a continuously operating prime mover. Such a system is obviously most efficient and elastic in operation, and lends itself to great advantages, as will hereinafter appear.

With the above and other objects in view, as will hereinafter appear, my invention comprises the features of construction and operation set forth in the following specification and illustrated in the accompanying drawings. In such drawings, annexed hereto and forming a part of this specification, I have shown certain specific embodiments

of my invention, but it will be understood that the invention can be otherwise embodied, and that the drawing is not to be construed as defining or limiting the scope of the invention, the claim appended to this specification being relied upon for that purpose.

Referring to the figures of the drawing, Fig. 1 is a front elevation of an apparatus embodying my improved pumping system;

Fig. 2 is a plan view thereof;

Fig. 3 is a vertical sectional view of a valve-controlling mechanism shown in Fig. 1;

Fig. 4 is a cross-sectional view thereof on line IV—IV of Fig. 3;

Fig. 5 is a semi-diagrammatic view showing the construction and operation of my improved system;

Fig. 6 is a fragmentary view showing a portion of Fig. 5 in a different operating position;

Fig. 7 is a vertical sectional view through a controlling valve, taken on line VII—VII of Fig. 2;

Fig. 8 is a like view with the valve parts in another position;

Fig. 9 is a horizontal sectional view through the valve on line IX—IX of Fig. 7;

Fig. 10 is a vertical sectional view through the valve on line X—X of Fig. 8;

Fig. 11 is a diagrammatic view showing a modified arrangement of my invention.

It should be understood that the system and mechanism shown in Fig. 5 are in general the same as those shown in Fig. 1 and Fig. 2. The same reference characters are therefore used on like parts in these views. Other reference characters are used to designate parts which are different. Figs. 1 and 2 show my apparatus as actually constructed, while Fig. 5 shows the same in simpler form and somewhat diagrammatically.

Referring more specifically to the drawing, 1 indicates the tube of an oil well, over which is mounted my improved pumping system, including a supporting base 2 for the pumping unit 3. This unit includes a pair of counterbalancing cylinders 4 carried directly on the base and having pistons 5 operating therein. Piston rods 6 extend upwardly from the pistons 5 through stuffing boxes 7 and guides 8. A cross head 9 con-

ncts the upper end of the rods 6 with the upper end of a piston rod 10. This rod 10 is connected to a piston 11 operating in a cylinder 12 carried on the frame above and 5 between the cylinders 4. The piston 11 and cylinder 12 comprise the power unit and the pistons 5 and cylinders 4 comprise the counterbalancing unit.

Co-operating with the pumping unit are 10 a pair of enclosed tanks 13 and 14 respectively adapted to operate in conjunction with the power cylinder 12 and the counterbalancing cylinders 4. For convenience the tank 13 is mounted on the tank 14 as illustrated. I preferably term the tank 13 the 15 storage tank or chamber, since energy in the form of fluid pressure is adapted to be stored up therein for operating the piston 11 in the cylinder 12. I term the tank 14 the balance chamber since the fluid pressure therein is 20 adapted to counterbalance the weight of the pump rods and other weight thereon as hereinafter described. Water or other operating liquid is provided in the lower portions of 25 these chambers and the remaining space therein is filled with compressed air.

An open tank 15 which I term the surge tank is provided for receiving the spent water from the power cylinder 12 through a 30 pipe 16 and other connections hereinafter described. A rotary pump 17 driven by a motor 18 is adapted to operate continuously to pump water from the tank 15 through a pipe 19 into the tank 13 under pressure. 35 Chambers 20 having slotted connections 21 with the bottoms of the cylinders 4 are interconnected by a pipe 22 and connected to the bottom of the tank 14 by a pipe 23.

As illustrated in Figs. 5 and 6 a chamber 40 24 having slotted communication 25 with the bottom of the cylinder 12 is connected by pipes 26 and 27 to the bottom of the tank 13, a valve 28 being interposed in this connection between the pipes 26 and 27. The 45 valve also has an outlet 29 to the pipe 16. The flow of fluid through the valve is controlled by a sliding valve member 30. In Fig. 5 this member is shown in its lower position wherein the pipe 26 is in communication with the outlet 29. In Fig. 6 the member is shown in its upper position wherein the pipe 26 is in communication with the pipe 27 and the outlet 29 is closed.

The position of the valve member 30 is 50 controlled by fluid pressure through an auxiliary controlling valve 31 having a port 31' therein adapted to connect the bottom chamber of the valve to the pipe 16 through pipes 32 and 33 (as in Fig. 5) or to connect the bottom chamber of the valve to the pipe 27 through pipes 32 and 34 (as in Fig. 6). The controlling valve 31 is adapted to be automatically rotated to its two positions illustrated by the reciprocation of the power piston 55 11 in the manner now to be described.

Means for automatically operating the controlling valve 31 at the ends of the piston strokes is shown in Figs. 1 and 2. An arm 35 on the valve shaft 36 is connected by a link 37 to an arm 38 on a vertical rocker 70 shaft 39. This shaft 39 carries upper and lower arms 40 and 41 on opposite sides of a rod 42 reciprocated with the piston 11. This rod carries a double cam 43 co-operating with the arms 40 and 41. At the end of the 75 up stroke the cam engages the arm 40 and rotates the valve 31 to the position shown in Fig. 5 and at the end of the down stroke the cam engages the arm 41 and rotates the valve to the position shown in Fig. 6.

The operation of the mechanism above described is as follows:

It will be understood that the pump 17 is continuously operating to pump water from the surge tank 15 into the storage tank 13 85 under pressure, the air in the tank 13 being under compression. As illustrated in Fig. 5 the piston 11 is connected to the sucker rods 44 through a rod 45 extending from the bottom of the piston through a stuffing 90 box 46, the sucker rods extending downwardly into the casing 1 in the usual manner. The amount of water in the tank 14 and the compression of the air therein are such that the same react on the pistons 5 95 within the cylinder 4 to support or counterbalance about nine-tenths of the weight of the sucker rods. The remaining one-tenth of such weight is sufficient to cause the rods and pumping mechanism to drop by gravity 100 when permitted to do so.

As illustrated in Fig. 5, the pump has just completed its up stroke and the valve 31 has been automatically turned from the position shown in Fig. 6 to the position shown in 105 Fig. 5. In such position of the valve 31 the upward pressure on the valve member 30 has been relieved through the pipes 16, 33 and 32, and the member has thereupon dropped to the position shown in Fig. 5. 110 Communication is thereby established from the cylinder chamber 24 to the outlet pipe 16. The power head and sucker rods thereupon drop by gravity, the water in the cylinder 12 escaping through the pipe 16 to the 115 surge tank 15.

When the power head and piston 11 reach the bottom of their stroke the cam 43 engages the arm 41 and rotates the valve 31 to the position shown in Fig. 6. The upward 120 pressure on the valve member 30 from the pipe 27 through the pipe 34 thereupon forces the valve member upward to the position shown in Fig. 6, whereby communication is established between the tank 13 and the cylinder 12. The piston 11 and the power head are thereupon raised on the up stroke until the valve 31 is again turned by the cam 43 125 engaging the arm 40.

Pressure gauges 47 may be provided on 130

the tanks 13 and 14 for indicating the pressure of the air and water therein. Water glasses 48 and 49 are also provided for indicating the amount of water and air in the tanks. Air and water transfer piping 50 is also provided between the two tanks whereby air or water can be transferred from one to the other. This piping connects with the air and water portions of the tank 13 at 51 10 and 52 and of tank 14 at 53 and a lower position not shown. By manipulating valves 54, 55 and 56 and another lower valve, air or water can be readily transferred from one tank to the other. The pipe 50 at its lower

15 end 57 is connected with the pipe 23 leading into the cylinders 4 and is controlled by a valve 58. By this arrangement the piston group can be moved to any position, either for slow operation, adjustments or repairs, 20 without opening the large main valve 28. A valve-controlled pipe 59 is also provided for discharging any surplus fluid from the tank 13 into the surge tank 15.

It is of course essential that the speed of 25 operation of the power head be controlled, and in Figs. 1 to 4 I have illustrated a novel valve means for this purpose. In the piping connecting the cylinder 12 with the tank 13 is interposed the valve controlling mechanism 60 and between the cylinders 4 and tank 14 I interpose the valve controlling mechanism 61. The mechanism 60 controls the flow of fluid only in one direction, that is from the tank 13 to the cylinder 12, while 30 mechanism 61 controls the flow of fluid in both directions. The construction of these two mechanisms is the same except that mechanism 60 includes a single valve and mechanism 61 includes a double valve.

40 The construction of the mechanism 61 is shown in detail in Figs. 3 and 4. A valve 62 is slidably carried on a rod 63 supported at 64 and threaded into the body member 65 at 66. A spring 67 is mounted on the rod between the valve and a bushing 68 secured to the rod. This spring normally operates to hold the valve away from its seat 69 as illustrated in full lines. The compressing action of the spring on the valve can be varied by rotating the rod and securing the same in adjusted position by the lock nut 70. Under a normal flow of liquid through the valve the spring will hold the same in the position indicated in full lines, wherein the liquid can flow therethrough between the valve and its seat. If the fluid pressure becomes greater than normal the action of the liquid against the face 62' of this valve will force the valve towards its seat against the action of the spring. It will be understood that a valve like the right-hand portion of Fig. 3 is provided at 60 and that two valves facing in opposite directions as shown in Fig. 3 are provided at 61.

45 While the valve 28 shown in Figs. 5 and 6

may be used in the pumping system, I prefer to use a valve of the type shown generally in Figs. 1 and 2 and in detail in Figs. 7, 8, 9 and 10. This valve, which is quite similar to the valve 28, comprises a body portion 71 having an inlet 72 from the tank 13, an outlet 73 to the cylinder 12 and an outlet 74 to the pipe 16. The flow of fluid through this valve is controlled by a valve member 75 similar to the member 30 of valve 28 shown in Figs. 5 and 6. The auxiliary controlling valve for the member 75 is a sliding cut-off valve 76 operated by an arm 77 on the valve shaft 36.

In Fig. 8 the member 75 is shown in a position wherein the piston 11 is ascending, the water flowing from the tank 13 through the port 72, valve chamber 75', port 73 to the cylinder 12. The member 75 is held in the position indicated by fluid pressure passing 80 from port 72 and valve chamber 75' through port 78 into the auxiliary valve chamber 79, ports 80 and 81 into the chamber 82 behind the member 75. The member 75 is thereby held forced to the right (Fig. 8). 90

When the piston reaches the top of its stroke the cam 43 engages the arm 40 and rotates the shafts 39 and 36 to slide the valve 76 from the position shown in Fig. 8 to the position shown in Fig. 7. Communication 95 between the ports 78 and 80 is thereby cut off and communication established from port 80 through cut-off valve port 83, ports 84, 85 and 86 to the outlet 74. The pressure on the rear face of the member 75 at 82 is thereupon relieved, and, the fluid pressure area on the member at 87 being greater than the fluid pressure area thereon at 89, the member is forced from the position shown in Fig. 8 to that shown in Figs. 7 and 9. In this 100 position communication between the inlet 72 and the outlet 73 is cut off, and communication is established between the port 73 and the outlet 74. The water from the cylinder 12 thereupon passes from the cylinder 110 through the valve 71 to the outlet 16, permitting the piston 11 to descend.

It should be understood that the construction illustrated and above described can be considerably modified within the scope of my invention. In Fig. 11 I have illustrated a slight modification thereof. It is well known that oil wells are commonly pumped from a central power plant which cares for the pumping of a dozen or more wells. My invention is particularly applicable to such a centralized system of pumping. 115

In Fig. 11 I have illustrated four widely separated pumping units 90, each including a base 2, a pumping unit 3, and tanks 13 and 14, substantially as illustrated in detail in Fig. 5. It will be understood that each of these units is located at a well to be pumped. I provide fluid under pressure to the tanks 120 13 from a central power plant 91 having a 130

rotary pump 17' operated by a motor 18' like that illustrated in Figs. 2 and 5. A central surge tank 15' is also provided adjacent and in connection with the pump 17'. Piping 92 connects the pump 17' with the tank 13 and piping 93 is provided for carrying the waste water from the pumps 3 to the surge tank 15'.

A suitable reducing valve 94 is provided in 10 the pipe 92 at each tank 13 which automatically regulates the pressure in each tank to a predetermined amount necessary to operate the power head. Also the discharging waters through the piping 93 can be made to 15 operate signals at the central plant for indicating the proper functioning of each individual power head and its rate of travel. This operation can of course be determined in a general way merely by observing the 20 discharge of the waters from the pipes 93 into the tank 15'.

The operation of the system shown in Fig. 11 is substantially the same as that described in reference to Figs. 1, 2 and 5. The pump 25 17' operates continuously to force water from the tank 15' to the tanks 13 under pressure. This water from tanks 13 is used in the manner already described to operate the well pumps, the waste water returning to the 30 surge tank through the piping 93.

It is believed that the advantages of my 35 improved pumping system will be obvious. The load carried by the pumping piston at each well is counterbalanced by fluid pressure, as has been described. This load is considerable, and the counterbalancing thereof not only adds smoothness and uniformity to the pumping operation but great efficiency is obtained by the storing up of the energy of the downward stroke to help lift the weight of rods and oil on the up-stroke. These rods in a 5,000-foot well weigh about 8,450 40 pounds, and the weight of oil thereon is about 9,500 pounds.

45 It will be understood that the weight of oil is carried by the rods on the up-stroke and released on the down stroke. The great length of rods and the great weight of oil

thereon cause the rods to stretch considerably at each up-stroke. Ordinarily this 50 stretch is about 43 inches. This stretch must of course be absorbed by giving the rods a very long pumping stroke. My system is particularly applicable to such a long stroke, 55 since the cylinders 4 and 12 can be made in any length desired. This stroke of the rods causes a considerable loss in power in the mechanisms in present use, since in such mechanisms the length of stroke obtained is 60 limited.

Reciprocating machinery of the crank type when used on strokes of more than 30 inches requires enormous masses of metal structure to maintain alignment and to withstand the great angular thrusts of the connecting rods. Much effective energy is used in overcoming friction of crossheads, bearings and other moving surfaces, which might be directly applied in doing useful work. The mechanism comprising my invention 70 operates with great smoothness and uniformity from a continuously operating prime mover and avoids the objections and great loss of power of the pumping mechanisms now in use.

Having thus described my invention, what I claim and desire to secure by Letters Patent is:

A pumping system comprising the combination of a cylinder, a piston operating 80 therein, a relatively large tank in communication with the cylinder, means providing fluid to the tank under pressure, a valve between the tank and cylinder for controlling the flow of fluid to the cylinder, means automatically operating the valve in timed relation with the piston movements, a second cylinder and a piston therein operatably connected to the first piston, and a chamber 85 in communication with the second cylinder 90 whereby a fluid medium is confined for compression by movement of the pistons in one direction to store up power for impelling the pistons in the opposite direction when the latter are free to so move.

WILLIAM E. HUBBARD.
